(57) **CLAIM**

The ornamental design for a yoke assembly for a surgical instrument, as shown and described.

DESCRIPTION

FIG. 1 is a top perspective view of a yoke assembly for a surgical instrument;

FIG. 2 is a bottom perspective view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a back view thereof.

The broken lines shown in the figures are included for the purpose of illustrating portions of the yoke assembly for a surgical instrument and form no part of the claimed design.

1 Claim, 4 Drawing Sheets
